UNITED STATES PATENT OFFICE.

SAMUEL M. HERBER, OF INZA, MISSOURI.

DISTILLATION OF OIL.

1,227,558.

Specification of Letters Patent.

Patented May 22, 1917.

Application filed August 7, 1915. Serial No. 44,299.

To all whom it may concern:

Be it known that I, SAMUEL M. HERBER, a citizen of the United States, residing at Inza, in the county of Buchanan and State of Missouri, have invented certain new and useful Improvements in Distillation of Oil; and I do hereby declare the following to be a full, clear, and exact description of the invention, such as will enable others skilled in the art to which it appertains to make and use the same.

My invention relates to the distillation of oil or other substances and more particularly to a distilling apparatus and my object among others is to provide a retort presenting a maximum heating surface for the contents, and with this and other objects in view, I so mount my retort that it may be readily rotated continuously or intermittently as desired, whereby the heating units will be continuously distributed throughout the entire surface.

With the foregoing and other objects in view, I desire to call attention to the accompanying drawings which are made a part of this application and in which,

Figure 1 is a longitudinal central sectional view of my retort complete ready for use.

Fig. 2 is a central transverse sectional view of my invention.

For convenience of reference to the various details of my invention and coöperating accessories, numerals will be employed, the same numeral applying to a corresponding part throughout the several views.

In materializing my invention, I provide a suitable support 1 of any desired character and upon which I erect the housing 2 and within said housing, thus or otherwise formed, I rotatably mount my heating chamber or retort 3, preferably of cylindrical form and mounted horizontally as shown. To each end section 4 of the cylindrical body or retort 3, I secure in any desired manner the supporting trunnions 5, which, as will be observed, are hollow or tubular in form and mounted upon suitable bearings 6 placed in a contiguous part of the housing 2 and said trunnions being rigidly secured to the end section 4, rotate with the retort as will be hereinafter fully set forth.

It will be observed that the inner ends 7 of the hollow trunnions 5 are flared in order to more reliably direct the heavier portions of distillation into the distributor which, as will be observed, is a trough like member 8

suspended upon the pipe 9 by suitable brackets or arms 8^a as will be clearly apparent.

Extending through the hollow trunnions 5 and concentrically therewith, I dispose the feed pipe 9 which, within the retort, is provided with a pair of downwardly extending arms or branches 10, one at each end of the retort, and connected with the perforated delivery pipe section proper 11, whereby the oil, or other substance, to be treated may be delivered at will directly into the bottom of the retort or on either side of the bottom as desired.

At the outer end of each of the hollow trunnions, I provide a suitable form of stuffing box 12 whereby the gaseous substances will be prevented from escaping and at the same time permitting the delivery pipe 9 to be turned at will, by moving the perforated delivery pipe to any desired point by means of the controlling lever 13 coöperating with the ratchet and detent mechanism 14 disposed upon the bracket 15 or said lever will be controlled by any suitable device. By said means or the equivalent thereof it is obvious that the delivery or feed pipe 9 may be freely turned so as to dispose the perforated discharging pipe section directly in the bottom of the retort as stated, or at either side thereof, as may be deemed desirable, this movement or change of the position of the perforated delivery pipe 11 being indicated by dotted lines in Fig. 2.

I also provide the hollow trunnions 5 with a plurality of openings 16 whereby the gaseous products of distillation may freely escape into the chambers 17 through the conveyer pipes 18, as clearly shown in Fig. 1 of the drawings.

In order to prevent leakage throughout the bearing surface of the trunnions, I provide stuffing boxes 19 which will be obviously necessary. The entire retort, thus, or otherwise mounted, may be continuously or intermittently rotated or turned in either direction by any suitable driving mechanism, though I preferably employ a suitable gear 20 meshing with a corresponding worm 21 and connected with any suitable source of power. My retort when thus placed within a suitable casing or housing 2 will be thoroughly and easily heated throughout its entire surface, the products of combustion being permitted to escape through the vent opening 22 or equivalent means. Any suitable source of heat may be utilized, though

preferably I employ a suitable gas burner 23 which may consist of one or a plurality of perforated delivery pipes, as shown in Fig. 2, the said burners or delivery pipes being located beneath any suitable form of baffle plate 24, as of clay or the like, whereby the flame will not impinge directly upon the outer surface of the retort, inasmuch as the said baffle plate will tend to more evenly distribute the intensity of the heat and prevent the concentration thereof upon only one part of such surface as will be obvious.

In order to render easy access to the interior of my retort, I provide a suitable man hole 25 and at a proper point in the end wall of the housing 2 I provide a corresponding opening 26 and a suitable closure 27 therefor, whereby my retort may be readily cleansed of accumulated or incrusted products of distillation, which will in time become very securely fixed in the inner surface of the retort. Obviously the gaseous products of distillation will pass from the chamber 17 and through the delivery pipes 27 and 28 into any suitable form of condenser 29, it being understood that proper controlling valves 30 and 31 are provided at suitable points.

In like manner, the contents of the condenser are delivered into any suitable form of tank 32 from whence the lighter and heavier products may be withdrawn through the pipe sections 33 and 34 respectively.

I desire it to be understood that my invention in thus providing a rotating retort may be materialized in various ways, as for instance, the said retort may be wholly supported upon the end bearings provided for the hollow trunnions; or a suitable track way 35 may be located at either or both ends of the retort and a continuous track or collar 36 secured to the end of the retort whereby said track or collar will rest directly upon a plurality of rollers or wheels 37 or equivalent anti-friction devices, thus enabling the retort to be easily turned in either direction at will.

Obviously in the distilling process, the gaseous substances will pass upward through the hollow trunnions and the opening 16 therein and thence through the chambers 17 and pipes leading to the condenser or worm 29, while the heavier products carried by the gaseous substances will drain downward from the chambers 17 thence into the hollow trunnions and be delivered by the inner flared ends thereof into the perforated trough like member 8, the object of the perforation in said trough like distributor being to insure that such condensation products will be uniformly distributed over the hollow of the retort.

It will be understood that in carrying out my improved process of oil distillation, wherein I employ lime as an agent, as fully

set forth in my Letters Patent of the United States No. 1,111,580, there is a tendency for the lime and the residuum of the oil to become caked or incrusted at the bottom of the retort or directly over the flame and obviously by partially rotating the retort after incrystation has been formed in the lower portion thereof, I am thus enabled to present an entirely clean surface of the retort for the action of the heat, thus presenting a new, clean section, free from incrystation of carbon or other residuum and consequently by this plan of rotation, or partial rotation of the retort, I practically multiply the capacity of my retort six or eight fold. I may at times find it desirable to continuously rotate the retort, though it may be intermittently rotated or partially turned so as to present a clean or unincrusted surface to the action of the heat, all of which will be clearly apparent and within the choice of the operator.

It will be understood that the oil or other substance to be treated may be introduced into the retort through the feed pipe 9 and that said pipe may also be utilized to introduce steam or air into the retort, or the said feed pipe may be employed solely for the introduction of steam or air and other suitable means may be provided for the introduction of the oil as may be deemed most desirable.

It is furthermore obvious that a plurality of my rotatable retorts may be provided and all processes connected with the same source of power so that they may be continuously or intermittently rotated as may be deemed productive of the best results.

While I have described the preferred combination and construction of parts deemed necessary to materialize my invention, I desire to comprehend in this application all substantial substitutes and equivalents.

Having thus fully described my invention what I claim as new and desire to secure by Letters Patent of the United States, is:—

1. In a distilling appliance, the herein described rotatable retort, consisting of the cylindrical body proper having hollow trunnions, provided with a suitable support and bearings therefor; separating domes; a pipe connection between each dome and one of said hollow trunnions, said trunnions and bearings having registering apertures to communicate with said pipe connections; a housing for the retort; means to rotate the retort, and additional means to introduce into the retort the substance to be treated and permit the gaseous products to escape therefrom.

2. The herein described distilling appliance consisting of a suitable housing; a retort within said housing and supported by hollow trunnions, bearings in a contiguous part of the housing for said trunnions,

- means to rotate said retort, inwardly directed extensions of said hollow trunnions provided with a flared terminal, a feed pipe mounted within the hollow trunnions and 5 extending throughout the retort, a controlling handle for the free protruding end of said feed pipe, a perforated trough like member supported upon said feed pipe within the retort whereby said trough like member will receive at each end the liquefied heavier distillates.
3. In a distilling appliance, a retort having separatory domes; means to rotatably mount the retort; a condenser; pipe connections between the retort, the condenser and the separatory domes, said pipe connections being adapted to introduce oil into the retort and permit the gaseous products of distillation to pass freely into said domes 10 and the heavier particles carried into the dome to return to the retort, and suitable means to freely rotate the retort in either direction.
4. In a distillation apparatus; a rotatable retort; means to operatively mount the same in position; suitable means to apply heat to the retort; hollow trunnions extending from each end of the retort; domes for receiving the products of distillation; suitable connections between the retort and said domes whereby the lighter products of distillation will pass out of the upper portions of the domes and the heavier particles will be again returned to the retort.
- 35 5. In a distillation apparatus; a rotatable retort; a suitable housing therefor; means to supply the desired degree of heat; means to rotate the retort; means to independently introduce oil and steam into the retort; receiving domes for the products of distillation and pipe connections for said domes adapted to deliver at any desired point the finished products of distillation and return to the retort all unfinished products.
6. In a distillation apparatus; a rotatable retort; a housing therefor; a fuel combustion chamber; a baffle plate for receiving and holding the initial heat in engagement with the lower portion of the retort; hollow trunnions extending from each end of the retort; means to deliver through the hollow trunnions oil and steam independently into the interior of the retort; receiving domes for the products of distillation; and means passing outward through the hollow trunnions 40 into connection with said domes whereby the products of distillation will be delivered into the upper portion of the dome; independent means to reconvey the unfinished products of distillation back into the retort; a condenser and suitable means to deliver the finished products of distillation from the domes into the condenser.
- In testimony whereof I have signed my name to this specification in the presence of 45 two subscribing witnesses.
